UNITED STATES PATENT OFFICE.

ELEANOR JOHNSON, OF CENTRALIA, WASHINGTON.

REPAIRER AND SEALER.

1,244,984.

Specification of Letters Patent. Patented Oct. 30, 1917.

Application filed January 13, 1917. Serial No. 142,157.

To all whom it may concern:

Be it known that I, ELEANOR JOHNSON, a citizen of the United States, residing at Centralia, in the county of Lewis and State 5 of Washington, have invented certain new and useful Improvements in Repairers and Sealers; and I do hereby declare the following to be a full, clear, and exact description of the invention, such as will enable 10 others skilled in the art to which it appertains to make and use the same.

This invention relates to a repairer and sealer and one of its objects is the provision of a device of this character especially 15 adapted for use on fruit jars or the like, for repairing the covers after they have once been used and removed from the jars, thus rendering it possible to use the covers several times.

20 Another object of this invention is to provide means for forcing the bulge out of the cover which is caused by accumulation of gas within the jar, thus making it easy to remove the cover from the jar.

25 A further object of this invention is to provide a cover engaging member having handles, one of which carries a set bolt for engaging the lip of a cover, whereby upon rotating the cover engaging member freely 30 upon the cover, the set bolt will straighten the lip of the cover so as to form an air-tight connection between the jar and the cover.

35 A still further object of this invention is the provision of a repairer and sealer of the above stated character, which shall be simple, durable and efficient, and which may be manufactured and sold at a comparatively low cost.

40 With these and other objects in view as will become more apparent as the description proceeds, the invention consists in certain novel features of construction, combination and arrangement of parts as will 45 be hereinafter more fully described and claimed.

For a complete understanding of my invention, reference will be had to the following description and accompanying drawings, in which;

Figure 1 is a perspective view of a repairer and sealer constructed in accordance with my invention,

Fig. 2 is a side elevation of the same illus-

trating the repairer and sealer applied to a 55 jar cover.

Referring in detail to the drawing, the numeral 1 indicates a substantially circular cover engaging member constructed from a substantially heavy gage wire. The wire is 60 first bent to form the substantially circular cover engaging member and one end thereof is bent to form a pair of relatively spaced bars 2, which form a handle 3. The end of the wire after constructing the outermost bar of the handle 3 is looped about 65 the other bar as illustrated at 4 and has its free end bent to form a catch 5.

The other end of the wire after forming the cover engaging member 1 is then bent to 70 form oppositely directed loops 6 and 7. The wire after forming the loop 7 is bent to form a pair of relatively spaced and parallel extending bars 7' which form a handle 8. After the wire has formed the handle 8, 75 it is passed through the loop 6 and about the loop 7 as clearly illustrated in Fig. 1 and is bent to extend across the cover-engaging member as illustrated at 9 to form an arm. The end of the arm is bent to form a hook 80 10 for engaging the cover engaging member 1. The arm 9 is offset downwardly as illustrated at 10 for an engagement with the top of a jar cover 11 as illustrated in Fig. 2 and which is secured to a 85 jar 12 in the usual manner or by screw-threads as clearly illustrated in Fig. 2. The cover 11 is provided with the usual lip 13 for engaging the rubber gasket 14 employed upon jars of this type to establish 90 an air tight connection between the cover and the jar.

In operation, the cover engaging member 1 is placed about the cover as illustrated in Fig. 2 permitting the arm 9 to overlie the 95 same and by moving the handles 3 and 8, in the direction of each other, the member 1 will tightly grip the cover 11 whereby the cover may be turned off or on the jar 12 as desired. If there has been an accumulation 100 of gas within the jar 12, it will cause the top of the cover to bulge, thus contracting the cover upon the jar making it very difficult to remove. To remove the bulge within the top of the cover caused by the accumulation of gas within the jar 12, the hook 9 is fastened to the member 1 and by rotating 105 the member 1 freely upon the cover 11

with a slightly downward pressure thereon, the bulge within the cover will be depressed, thus relieving the strain at a connection of the cover upon the jar, whereby upon moving the handles 3 and 8 together, the member 1 will grip the cover and by rotating the member 1, the cover 11 will be removed from the jar 12.

A threaded bearing 15 is secured within 10 the loop 7 and has threaded thereto a set bolt 16 having a handle 17 on one end and its opposite end pointed as illustrated at 18.

It has been the practice when the cover 11 becomes swollen or snugly fits the jar 12 to 15 insert a knife or like instrument under the gasket 14 so as to permit gas to escape from within the jar so as to render it possible to remove the cover from the jar, and by so doing, the lip 13 has been bent out of shape rendering the cover useless the second time, owing 20 to the fact that if the lip 13 is bent out of shape, it will not seat properly upon the gasket 14, thereby preventing a leakage between the cover and the jar. To render the 25 cover again useful, the member 1 is placed upon the cover as illustrated in Fig. 2 and the set bolt 16 is threaded within the bearing 15 until the pointed end 18 engages the lip 13 and by rotating the member 1 upon the cover 11, the set bolt 16 will travel 30 about the lip 13 and straighten the same of any defects or bends that may be therein, thus rendering the cover of use for several times upon a jar.

35 The catch 5 upon the end of the wire which constructs the handle 3 engages the innermost bar 7 of the handle 8, whereby the handles are prevented from spreading over a given distance, whereby the member 40 1 is permitted to expand sufficiently to receive the cover, thus obviating the necessity of gripping both of the handles at one time, when desiring to rotate the member 1 upon the cover to either straighten the lip 45 13 or remove bulges from the top of the cover.

In canning preserves or fruit while in a hot condition, it has been found difficult sometimes to obtain an air-tight seal between 50 the cover and the jar, even when new covers are used and by placing the cover engaging member about the cover and screwing down the adjusting bolt until it engages the lip of the cover and by rotating the handles and 55 cover engaging member upon the cover, the lip will be straightened out upon the gasket between the cover and the jar, thus establishing an air-tight connection.

While I have shown and described the 60 preferred embodiment of my invention, it will be understood that minor changes in construction, combination and arrangement of parts may be made without departing from the spirit and scope of the invention 65 as claimed.

Having thus described my invention, what is claimed is:

1. A device of the character set forth comprising a cover-engaging member, handles formed on the cover-engaging member for 70 clamping said member upon the cover of a jar, and means adjustably carried by one of the handles for straightening the lip of a cover.

2. A device of the character set forth comprising a cover-engaging member, handles formed on said member, and a curved arm for removing the bulge from the top of a jar-cover. 75

3. A device of the character set forth comprising a jar-engaging member, handles formed on said jar engaging member to cause the member to grip a jar cover, and a bolt adjustably carried by one of the handles for engagement with the lip of the 80 cover to straighten the same.

4. A device of the character set forth comprising a cover-engaging member, handles formed on the cover engaging member for causing the member to grip a cover, a 85 threaded bearing carried by one of said handles, and an adjusting bolt threaded to the bearing and adapted to engage the lip of a cover to straighten the same.

5. A device of the character set forth comprising a cover-engaging member, handles formed on the cover-engaging member for causing the member to grip a cover, and an arm carried by one of the handles and adapted to overlie the cover of a jar and 90 engage the cover-engaging member to remove bulges from the cover upon rotation of said cover engaging member.

6. A device of the character set forth comprising a cover-engaging member, handles 105 carried by said cover-engaging member, and an arm formed on one of the handles and having its ends bent to engage the cover-engaging member, and said arm being offset to remove the bulges from the cover upon 110 rotating the cover-engaging member upon the cover.

7. A device of the character set forth comprising a single length of wire being first 115 bent to form a substantially circular cover-engaging member, the ends of the wire after forming the cover-engaging member being bent to form a pair of handles, one end of the wire after forming one of the handles being looped about itself and bent to form 120 a hook to engage the other handle, and the other end of the wire after forming the other handle being bent to form an arm for removing the bulge from a cover and having its free end bent to form a hook for engagement with the cover engaging member.

8. A device of the character set forth comprising a single length of wire first bent to form a cover-engaging member, one end of said wire being bent to form a handle, the 130

other end of said wire being bent to form a pair of oppositely directed loops, said wire after being bent to form the loop being bent to form a handle, the end of the 5 wire after forming the last mentioned handle being bent to extend through one of the loops and about the other loop at right angles thereto to form an arm for overlying the cover-engaging member, and having its

free end bent to form a hook for engaging 10 the cover engaging member, and an adjusting bolt carried by one of the loops.

In testimony whereof I affix my signature in presence of two witnesses.

ELEANOR JOHNSON.
